UNITED STATES PATENT OFFICE.

WILLIAM MILLER, OF GLASGOW, SCOTLAND.

FIRE-EXTINGUISHER.

SPECIFICATION forming part of Letters Patent No. 395,069, dated December 25, 1888.

Application filed October 25, 1887. Serial No. 253,286. (No model.)

To all whom it may concern:

Be it known that I, WILLIAM MILLER, a resident of Glasgow, Scotland, and a subject of the Queen of Great Britain and Ireland, 5 have invented a new and useful Improvement in Fire-Extinguishers, of which the following is a specification.

My invention relates to fire-extinguishing apparatus of the kind in which a carbonate 10 or bicarbonate dissolved in or contained with water is confined in a vessel along with an acid, which acid is kept separate until the apparatus has to be used, but is then made to mix with the carbonate or bicarbonate and 15 water and causes the evolution of carbonic-acid gas, resulting in the forcible expulsion of the solution and gas through a pipe and nozzle provided for the purpose of directing the jet on the fire.

20 My object is to construct such apparatus in an improved manner, in an extremely portable and convenient form, and so as not to be liable to premature action of the acid, while capable of being set in action with great 25 facility when required.

Fire-extinguishing apparatus made according to my invention is shown in the accompanying explanatory drawings, Figure 1 being a longitudinal section, and Fig. 2 a transverse section. Figs. 3 and 4 are longitudinal 30 and transverse sections, showing modifications of some parts of the apparatus.

The vessel A of my improved apparatus is a long tube-like cylinder of a size which can be 35 conveniently grasped in the hand, and which may be made of tinned iron or steel or other suitable thin metal. Covers B C are soldered or otherwise fixed on the ends, and to what may be regarded as the upper end, B, there 40 is fixed a wire loop, D, by which the apparatus can be hung upon a nail in a convenient position for being taken hold of when required for use. Through the same end, B, there projects the nozzle E of a pipe, F, which 45 extends inside nearly to the other end, a wire-gauze strainer, G, being fixed on the other end to prevent the pipe from being choked. The nozzle E is closed by a tightly-fitting rubber cap, H, which is withdrawn when the apparatus is about to be used.

The sulphuric or other acid is contained in a small glass bulb, J, which is hermetically closed, and is placed within a small cylinder, K, fixed to a bridge-piece, L, fixed across the vessel A, and having a hole made through its 55 middle. The acid-bulb J is introduced through the end cover, C, which is made with an internally-screwed neck provided with a screw-closing plug, M, the carbonate or bicarbonate and water being introduced through the same 60 opening before the acid-bulb J is put in. To the inner side of the plug M there is fixed a short tube, N, having inside of it a loose bolt, P, of cast-iron or other heavy substance.

My improved apparatus is set in action by 65 simple concussion transmitted through the shell of the vessel, there being no rod working through a packed or unpacked orifice, leakage through which can hardly be prevented. When required, the vessel A is simply grasped in the hand and its end M is struck smartly against a floor or any firm 70 hard substance. The concussion of the blow, acting through the loose bolt P, causes the breakage of the acid-bulb J, and the acid in 75 it immediately acts on the carbonate or bicarbonate and produces the desired result.

It is not essential to have a loose bolt, P, as simple concussion is quite sufficient.

In the modification shown in Figs. 3 and 4, 80 the end C is closed by a plain cap, Q, instead of a screw-plug, M, this cap Q being soldered in its place when the vessel has been charged. A tube, N, of thin metal is fixed to the inside 85 of the cap Q, and the acid-bulb J is in contact with the inner end of it. When required, the breaking of the acid-bulb J is easily effected by smartly striking the end cap, Q, once or oftener, against the floor or any firm hard substance.

When the screw-plug M is used the hanging loop D may be fixed at the same end of the vessel, so that the plug may be uppermost when the apparatus is hung up; and it may be mentioned that when the loose bolt P is used 95 a blow with or on either end of the vessel is equally effective in breaking the acid-bulb J.

What I claim as my invention is—

The herein-described portable fire-extinguisher adapted to be grasped in the hand, 100

and comprising an elongated thin metal cylinder having a discharge-nozzle and containing a sealed glass acid-vessel and a contact-piece between the body of the cylinder and the glass vessel to transmit concussion on the outside to the glass vessel within for the breakage of the latter, substantially as described.

In testimony whereof I have signed my name to this specification in the presence of two to subscribing witnesses.

WM. MILLER.
